UNITED STATES PATENT OFFICE

2,688,109

SWITCHBOARD ENCLOSURE WITH INTER-
CONNECTING WIRING CHANNELSRoy P. Holland, Milwaukee, Wis., assignor to
Allis-Chalmers Manufacturing Company, Mil-
waukee, Wis.

Application October 29, 1951, Serial No. 253,713

3 Claims. (CL. 317—122)

1

This invention relates generally to switchboards and more particularly to switchboards of the cubicle type in which most of the wiring is concealed.

Many attempts have been made to provide steel switchboards of the concealed wire cubicle type which are suitable for adoption as a standard construction. However, a majority of the prior art attempts at this type of standardization have been unsuccessful because of the failure to reduce the various sizes and types of switchboards to certain standard parts which remain the same regardless of the physical dimensions of the switchboard or cubicle. By not utilizing standard elements in the construction of steel switchboards, manufacturers had to make a complete set of drawings for each job in order that the units could be shop assembled. Thus, it is apparent that such a procedure requires the expenditure of a large amount of money for the making of drawings for each order received for a new switchboard or cubicle, even though it may be of a type previously constructed but of different dimensions.

In accordance with this invention a new and improved switchboard cubicle is provided which has a plurality of spaced upright members provided with flange forming channel members. Sheet metal panel members are mounted on the spaced upright members to form the walls of the cubicle. The top of the cubicle is a one piece metal member which is supported by the spaced upright members and formed to provide a pair of cross channel members. These cross channel members are arranged to interconnect with the upright flange channel members to provide two passageways up one wall of the cubicle and across the top thereof and down another wall of the cubicle. An interconnecting channel may be arranged across the top of the cubicle transversely of the cross channel members to provide a way for communication between the two passageways. A number of these unit switchboard structures may be interlocked or fitted together to form a multisection switchboard structure.

It is, therefore, one object of the present invention to provide a new and improved switchboard cubicle which may be economically designed and readily manufactured and installed.

Another object of this invention is to provide a new and improved switchboard cubicle in which standard elements of different shapes may be utilized to construct switchboard cubicles of various sizes and types.

A further object of this invention is to provide

2

a new and improved switchboard cubicle in which the cubicle walls and top are formed to provide channels which are adapted to contain conductors to be connected to the electrical control equipment mounted on the switchboard.

Objects and advantages other than those above set forth will be apparent from the following description when read in connection with the accompanying drawings, in which:

10 Fig. 1 is a view, in perspective, of a portion of a switchboard structure constructed in accordance with this invention;

Fig. 2 is a partial side view of the switchboard structure illustrated in Fig. 1;

15 Fig. 3 is a cross sectional view taken along the line III—III in Fig. 2 looking in the direction of the arrows;

Fig. 4 is a cross sectional view taken along the line IV—IV in Fig. 3 looking in the direction of the arrows;

20 Fig. 5 is a cross sectional view taken along the line V—V in Fig. 4 looking in the direction of the arrows;

Fig. 6 is a side view of the switchboard structure illustrated in Fig. 1 with door and side panels added; and

Fig. 7 is a cross sectional view taken along the line VII—VII in Fig. 6 looking in the direction of the arrows.

30 Referring more particularly to the drawing by characters of reference, Figs. 1 to 7, inclusive, illustrate the framework, front panels and top of a two cell cubicle of a multicell switchboard device. The framework shown for one cell comprises two pairs of spaced metal upright frame members 11, 12 and 13, 14, each having flanges

35 21 forming channels 15. The upright members are mounted on U-shaped steel members 16, 17 and when enclosed by metal panel members 18 and 19 and a top member 20 form a cubicle.

40 Flanges 21 are provided with a plurality of apertures 22 arranged along the length thereof.

The top member 20 of each cell comprises a single piece of metal such as sheet steel formed,

45 as shown more clearly in Fig. 5, to provide two channel cross members 25. The top is supported by the upright frame members 11, 12 and 13, 14 and is so arranged that the cross channel members 25 connect with channels 15 to provide pas-

50 sageways up one wall which may be the back of the cubicle and across the top thereof and down another wall which may be the front of the cubicle. Thus, wires 26 connected to a switch or other electrical control element 27 may be threaded through apertures 22 and up the chan-

nel 15 across the top of the cubicle by passing through cross channel members 25 and down channel 15 formed in the opposite upright member forming a part of the front of the cubicle and out apertures 22 to another electrical device. The walls are removable from the upright frame members without disturbing channel 15 which forms part of the passageway up the wall of the cubicle.

As shown in Figs. 1 and 3, a single cell may be combined with other cells to provide a multicell cubicle. This is accomplished by securing upright frame members 11 and 12 and 13 and 14 of two adjacent cells together. Wires or conductors in channel 15 of upright frame member 12 may be threaded into channel 15 of frame member 11 through axially aligned apertures 30 provided in frame members 11 and 12. Apertures 30 are also axially aligned in frame members 13 and 14 so that wires or conductors may be threaded from channel 15 of frame member 13 to channel 15 of frame member 14.

In order to thread wires or conductors between non-adjacent channels and to conceal the interconnecting wires, a cross passageway 31 is provided which is defined by a U-shaped interconnecting channel means or member 32 mounted to connect intermediate points of the cross channel members 25. Thus, if openings 33 are provided in cross channel members 25, wires may be threaded from one channel 15 up the wall of its cell, across the top to passageway 31 formed by U-shaped channel member 32 and through passageway 31 to any other cell in the multicell cubicle. The wire is substantially hidden or concealed or contained except at its entrance to channel 15 in one cell and its exit from channel 15 in another cell.

Switchboard cubicles as shown and described are usually provided with a swinging panel or door 34 (as shown in Figs. 6 and 7) arranged on one or on both ends of the cubicle to permit ready access to the interior of the cubicle. Right angle members 35 may be added to the structure, if desirable, to aid in handling the cubicle.

From the foregoing description, it is apparent that the structure described has numerous advantages over previously known switchboard structures. Since it is possible to produce the parts in large quantities, because of their wide application in switchboards of various types, and in view of the general simplification of the manner in which they may be fitted or interlocked together, the cost of producing steel switchboard structures can be materially reduced. Furthermore, large savings can be realized by the use of coded drawings and typical steel assembly drawings which can be prepared for cubicles of any certain type, but varied as to dimensions, thereby making it unnecessary to prepare complete drawings of the steel assemblies for each individual order as has been the previous practice among switchboard manufacturers.

Although but one embodiment of the present invention has been illustrated and described, it will be apparent to those skilled in the art that various changes and modifications may be made therein without departing from the spirit of the invention or from the scope of the appended claims.

It is claimed and desired to secure by Letters Patent:

1. A switchboard cubicle comprising a plurality of pairs of spaced metal upright frame members having flanges thereon forming channels, sheet metal panel members mounted on said frame members for providing walls of said cubicle, single piece sheet metal top members each supported by and extending between pairs of opposite upright frame members, each said single piece sheet metal top member being bent at ninety degrees along six parallel lines to form all four sides of each of two channel cross members which interconnect with said flange forming channels of opposite upright frame members to provide passageways up one wall of said cubicle and across the top thereof and down another wall of said cubicle, and U-shaped interconnecting channel means which is arranged transversely of intermediate points of said cross members to provide passageways extending between and interconnecting said cross channel members.

2. A switchboard cubicle comprising spaced metal upright frame members having flanges thereon forming channels, sheet metal panel members mounted on said frame members for forming walls of said cubicle, and a single piece sheet metal top member supported by and extending between said upright frame members, each said single piece sheet metal top member being bent at ninety degrees along six parallel lines to form all four sides of each of two channel cross members which have horizontal bottom webs and are arranged substantially perpendicular to said frame members and interconnect with said flanges of said upright frame members to provide passageways up one wall of said cubicle and across the top thereof and down another wall of said cubicle, and U-shaped interconnecting channel means which are arranged transversely of intermediate points of said cross members, said channel means having bottom webs at the same level as the bottom webs of said channel cross members to provide passageways extending between and interconnecting said channel cross members.

3. A switchboard cubicle comprising a plurality of pairs of spaced metal upright frame members having flanges thereon forming channels, sheet metal panel members mounted on said frame members for providing walls of said cubicle, and single piece sheet metal top members each supported by and extending between pairs of opposite upright frame members, each said single piece sheet metal top member being bent at ninety degrees along six parallel lines to form all four sides of each of two channel cross members which interconnect with said flange forming channels of opposite upright frame members to provide passageways up one wall of said cubicle and across the top thereof and down another wall of said cubicle.
